HIGH DENSITY ATTACHMENT FOR COMPRESSES FOR COTTON BALES

Filed Sept. 16, 1925

UNITED STATES PATENT OFFICE.

JOHN H. MACLEAN, ALFORD C. BARROWS, AND GEORGE W. LANGFORD, OF ANN ARBOR, MICHIGAN, ASSIGNEES TO ECONOMY BALER COMPANY, OF ANN ARBOR, MICHIGAN, A CORPORATION OF MICHIGAN.

HIGH-DENSITY ATTACHMENT FOR COMPRESSES FOR COTTON BALES.

Application filed September 16, 1925. Serial No. 56,752.

The invention relates to high density attachments for compresses for cotton bales and has for one of its objects the provision of a high density attachment which is actuated 5 from the movable platen of the compress. Another object is the provision of a high density attachment including a pivotal side platen which is swung from inoperative to operative positions by means of the movable 10 platen of the compress. A further object is the provision of means for moving a side platen of the high density attachment from inoperative to operative positions during the compression movement of the movable platen 15 of the compress and for releasing the side platen prior to the completion of the compression movement of the movable platen to allow the side platen to return to inoperative 20 position.

With these as well as other objects in view the invention resides in the novel features of construction as more fully hereinafter set forth.

In the drawings:—

Figure 1 is a side elevation of a compress for cotton bales having applied thereto a high density attachment embodying my invention;

Figure 2 is a sectional end elevation there- 30 of;

Figure 3 is an enlarged side elevation of a portion of the high density attachment.

The compress for cotton bales has the vertical frame 1, which extends below the floor 35 level into the pit 2. 3 is the upper platen which is stationary and fixedly secured to the frame 1 and 4 the lower platen which is vertically reciprocable from a position slightly below the floor level to a position near the 40 upper platen. The lower platen is fixedly secured upon the saddle 5, which is guided by the frame 1 and is vertically reciprocated by suitable means, including the toggle levers 6 which are connected at their lower ends to the 45 opposite ends of the saddle and at their upper ends to the frame and are actuated by means of the pitman rods 7. These rods are connected to the gears 8 forming part of the reduction gearing 9.

The high density attachment comprises the side platens 10 at the opposite sides of the compress and adapted to be moved from in-

operative to operative positions upon movement of the lower platen 4 of the compress. The side platens and their actuating mechanism are exactly the same and therefore but one side platen and its actuating mechanism will be described in detail. The side platen 10 is pivotally mounted upon the frame 1 of the compress at a point substantially below 55 the floor level by means of the pivot 11. In its inoperative position the side platen lies substantially below the floor level, while in its operative position the side platen extends vertically at the side of the compress to form 60 a side wall of the baling chamber. To swing the side platen upwardly and inwardly from inoperative to operative positions prior to the completion of the compression stroke of the lower platen 4, we have provided the projection 12 extending laterally from the saddle 5 and preferably in the nature of a roller 13 65 journaled upon the bracket 14. We have also provided the sectional tracks 15 upon the side platen and extending longitudinally thereof 70 and beyond its edges for engagement by the roller 13 during the compression stroke of the lower platen. These tracks are laterally offset so that during the initial compression stroke of the lower platen and substantially 75 prior to the time that the cotton bale is compressed between the lower platen and the upper platen the side platen is swung to operative position to laterally compress the cotton bale.

To permit tying or banding the compressed cotton bale when the lower platen of the compress is in its uppermost position we have provided means for releasing the side platen prior to the completion of the compression stroke of the lower platen. As specifically shown, each track 15 has a length such that when the side platen is in operative position the track terminates below the roller 13 when in the uppermost position of the lower platen, 80 so that the side platen is released just prior to the completion of the compression stroke of the lower platen and may return to inoperative position under the influence of gravity, this position being determined by suitable 85 means such as the stops 16.

To permit the return of the lower platen of the compress to its lowermost position, each track 15 upon the side platen is made sectional

to include the pivotal dogs 17 pivoted at 18 upon the side platen and adapted to swing downwardly and outwardly when the roller 13 engages their upper sides to allow this roller 5 to pass therethrough. These dogs are normally held in operative position by suitable means such as the springs 19 which after the downward movement of the roller return the dogs to positions to be engaged by the roller 10 when the lower platen is next raised. Also these dogs are suitably held from swinging upwardly above operative position by means of the lateral projections 20 upon the body 21 which supports each track upon the side 15 platens.

From the above description it will be readily seen that we have provided an improved construction of high density attachment for compresses for cotton bales in which the side 20 platens of the high density attachment are actuated by a very simple mechanism. It will also be seen that the arrangement is such that the side platens of the high density attachment are swung from inoperative to operative 25 positions during the compression stroke of the movable platen of the compress and released prior to the completion of this compression stroke so that they may return to inoperative positions and provide access for 30 tying or banding the compressed cotton bale. It will be further seen that the movable platen of the compress controls the movement of the side platens of the high density attachment. The side platens are so arranged relative to 35 the pivotal floor sections that when the former are swung upwardly and inwardly of their operative positions they swing the pivotal floor sections upwardly and outwardly to move a person or truck upon these floor sections away 40 from the compress.

What we claim as our invention is:

1. The combination with a compress for cotton bales including a platen and a second platen movable toward said first-mentioned 45 platen, of a high density attachment including a side platen and means for actuating said side platen from said movable platen.

2. The combination with a compress for cotton bales including a platen and a second 50 platen reciprocable toward and away from said first-mentioned platen of a high density attachment including a side platen and means connected to and movable with said reciprocable platen for moving said side platen 55 from inoperative to operative positions during the compression stroke of said reciprocable platen.

3. The combination with a compress for cotton bales including a platen and a second 60 platen movable toward said first-mentioned platen of a high density attachment including a pivotal side platen arranged to swing from inoperative to operative positions and means upon said first mentioned platen and 65 dependent upon movement thereof for swing-

ing said side platen from inoperative to operative positions.

4. The combination with a compress for cotton bales including a platen and a second platen movable toward said first-mentioned 70 platen, of a high density attachment including a side platen movable from inoperative to operative positions and a projection upon said first mentioned platen and engageable with said first mentioned side platen to move the 75 same from inoperative to operative positions.

5. The combination with a compress for cotton bales including a movable platen, of a high density attachment including a side platen and means for moving said side platen 80 from said first mentioned platen from inoperative to operative positions during the compression movement of said first mentioned platen and releasing said side platen prior to the completion of said compression movement.

6. The combination with a compress for cotton bales including a reciprocable platen, of a high density attachment including a side platen movable from inoperative to operative 90 positions and a projection upon said first mentioned platen and engageable with said side platen to move the same from inoperative to operative positions during the compression stroke of said first mentioned platen, said projection being disengaged from said side platen prior to the completion of said compression stroke to release said side platen.

7. The combination with a compress for cotton bales including a reciprocable platen, of a high density attachment including a side platen movable from inoperative to operative 100 positions during the compression stroke of said first mentioned platen, said projection being disengageable from said track prior to the completion of said compression stroke to release said side platen, and said side platen upon release being movable to inoperative position under the influence of gravity.

8. The combination with a compress for cotton bales including a movable platen, of a high density attachment including a side platen and means for moving said side platen from inoperative to operative positions during the compression movement of said first mentioned platen and releasing said side 115 platen prior to the completion of said compression movement to allow the same to return to inoperative position.

9. The combination with a compress for cotton bales, including a movable platen, of a high density attachment including a side platen, means for actuating said side platen from said movable platen, a pivotal floor section extending over said side platen when the latter is in inoperative position and engage- 120

able by said side platen upon movement of the latter by said movable platen to swing said floor section away from said compress.

10. The combination with a compress for 5 cotton bales including a platen and a second platen movable toward said first mentioned platen, a high density attachment including a side platen and means for actuating said side platen from said movable platen from

inoperative to operative positions and for 10 releasing the said platen prior to the completion of the compression movement.

In testimony whereof we affix our signatures.
